(57) **CLAIM**

The ornamental design for a vending machine cashless payment terminal, as shown and described.

DESCRIPTION

FIG. 1 perspective view of a vending machine cashless payment terminal shown with a mounting bracket;

FIG. 2 perspective view of the vending machine cashless payment terminal shown with surface of vending machine; FIG. 3 is a perspective view of the vending machine cashless payment terminal;

FIG. 4 is a front side plan view of the vending machine cashless payment terminal;

FIG. 5 is a left side plan view of the vending machine cashless payment terminal;

FIG. 6 is a right side plan view of the vending machine cashless payment terminal;

FIG. 7 is a back side plan view of the vending machine cashless payment terminal;

FIG. 8 is a top side plan view of the vending machine cashless payment terminal; and,

FIG. 9 is a bottom side plan view of the vending machine cashless payment terminal.

The broken lines in the drawings depict environmental structure, which forms no part of the claimed design.
